Filed Mar. 6, 1957, Ser. No. 644,350

1 Claim. (Cl. 290—38)

This invention relates to starting systems for internal combustion engines and is more particularly concerned with starting systems wherein the control of the actuation of the starter is accomplished without human assistance.

Internal combustion engines which are used as emergency sources of power frequently are equipped with automatic starting systems. That is, the energization of the starting system for the engine is initiated automatically in response to an outside event without human assistance or attention. Further, these engines frequently are installed at some remote location. Therefore, if these engines are to fulfill their expected function, the starting systems for these engines must be virtually fool-proof. While the starting systems which will be herein described may be used to supply cranking torque to other than stationary emergency power equipment, it is particularly suited to installations wherein the engine is started and operated without human attention.

On a typical starting system for an internal combustion engine, such as shown in U.S. Patent 2,716,895, the starting motor is provided with a starter drive. This starter drive includes a pinion gear which is moved into meshing engagement with the ring gear on the engine to be started. The starting motor when energized supplies the cranking torque to cause the engine to become self-operative. The movement of the starter drive pinion gear into meshing engagement with the ring gear is accomplished by a solenoid which not only moves the pinion gear into engagement but also closes the circuit to the starting motor. On occasion, it has been found that tooth abutment will occur between the pinion and the ring gear of the engine when the pinion gear is moved into engaging position. When this tooth end abutment occurs, the teeth of the pinion gear abut the end of the teeth of the ring gear and are prevented from passing into the spaces between the teeth of the ring gear. When this occurs, the solenoid of the starting system will continue to be energized to urge the pinion gear toward the meshing engagement. The current flow through the solenoid windings during these periods will be abnormally high and may ultimately cause the solenoid coil winding to become overheated. This overheating of the solenoid will ultimately result in a short which may result in failure of the entire starting system.

It is an object, therefore, of the present invention to prevent the overheating and resulting shorting of the solenoid in an automatic starting system for internal combustion engines.

In carrying out the above object, it is another object of the present invention to prevent overheating of the solenoid in an automatic starting motor apparatus for an internal combustion engine and to cause a recycling of the starting motor circuit in event tooth end abutment occurs between the pinion gear of the starting motor drive and the ring gear of the engine to be cranked.

Further objects and advantages of the present invention will be apparent from the following description, reference being had to the accompanying drawings wherein pre-

2

ferred embodiments of the present invention are clearly shown.

In the drawings:

5 The single figure illustrates an automatic starting motor system incorporating the features of the present invention.

In the drawing, the starting motor for the internal combustion engine, not shown, includes; a starting motor 20, a starter drive 22, a starter motor solenoid 24, a storage battery 26 and a means for controlling the 10 energization of the starting motor solenoid 22 and the starting motor 20.

The starting motor 20 is of the conventional type and the starter drive may also be of the conventional type and may include a sprag or roller type clutch 27 as, for 15 example, as disclosed in application, Serial No. 558,468, filed January 11, 1956, and assigned to the assignee of the present invention.

The solenoid 24 is provided with an outer casing 28 which, in practice, is usually attached to the frame of the 20 starting motor. The casing 28 encloses a pair of solenoid windings 30 and 32, a solenoid plunger 34, a magnetic pole piece 36 and a movable contact 38 which is arranged to engage the stationary contacts 40 and 41. The solenoid plunger 34 is suitably connected through a link 42 and a 25 lever 44 with the starter drive 22. The contact 40 is connected directly to the battery 26. The contact 41 is connected through a lead 46, to the field 48 of the starting motor 20, and the armature of the starting motor, not shown, to ground 50, from whence the circuit is complete to the ground 50 of the battery. Winding 30 of the solenoid is formed of relatively fine wire which has one 30 of its ends connected directly to ground 50 and the other end connected through a lead 52 to a circuit which will be later described. Winding 32, which is formed of

35 heavier wire, has one of its ends connected to lead 52 and its other end connected to the terminal for contact 41. From the above, it is apparent that when current is supplied from the battery through a means which will be later described, to lead 52, current will flow through both 40 windings 30 and 32. The current through winding 30 will be directly connected to ground 50 and the current flow through winding 32 will pass from the lower terminal 41 through lead 46, field 48 and the armature of starting motor to ground 50. When current flows through 45 these windings, the magnetic attraction set up in pole piece 36 will cause the solenoid plunger to move to the right, thereby moving the starter drive 22 so that the pinion 54 is moved toward the ring gear 56 which is connected to the engine to be started. If there is no abutment between the pinion gear 54 and ring gear 56, the teeth of the pinion gear will pass into engagement with the ring gear. When this occurs, the plunger 34 will 50 have moved sufficiently to the right to cause the contacts 38 to engage contacts 40 and 41 and complete the circuit between the battery and the starting motor so that the motor will become energized. Also, when the contact 55 38 closes the circuit through contacts 40 and 41, the winding 32 will be shorted out of the circuit so that the winding 30 will act as a hold-in winding to maintain the plunger in the attracted position. When the starting motor is energized, it will rotate the shaft 58 which will cause the pinion gear to be rotated to supply the cranking torque to the ring gear 56 of the engine.

The generating system which is used to charge the battery 26 forms a part of the control means for the starting system according to the present invention. In the embodiment shown, the generator 60 has one output lead 61 connected to ground 50. The other output lead 62 is connected through a junction 63 with the generator terminal 64 of a conventional current and voltage switch and regulator as used in present day automotive vehicles. The regulator 65 has an internal circuit that is prefer-

ably like that shown in the patent to Rice 2,811,677. The field 66 of the generator has one end connected to lead 62 and the other end connected to the field terminal 68 of the regulator 65. The battery terminal 70 of the regulator 65 is directly connected through leads 72 and 74 with the battery 26. The control circuit means for the starting motor also includes the circuit breaker 76, a solenoid relay 78, a diagrammatically shown vacuum switch 80 and a starting switch 82 all of which will be now described.

The solenoid relay 78 has an actuating coil 84 wound on a magnetic core 86 which will attract the armature 88 and cause engagement between the contacts 90 and 92 whenever the coil 84 is energized. The contact 90 is carried on the armature 88 and is connected in through the circuit breaker 76 with lead 52. The contact 92 is connected through a lead 94 and lead 74 with the battery 26. One end of the actuating coil 84 of the relay 78 is connected through a lead 96 with the junction 63. The other end of the coil 84 is connected through the vacuum switch 80 and the control switch 82 to lead 74 to battery 26.

The switch 82 is the main control switch and may be arranged to be either manually closed or closed automatically by some suitable means so as to be responsive to an outside event as for an example a failure in power which would require that the stationary engine be started to supply emergency electric current to a system. The switch 80 is preferably a pressure type switch which are well known which may be either connected to the oil pressure system of the engine which is to be started or to the engine vacuum. In either case the switch 80 is arranged so the contacts are normally closed when the engine is inoperative and will open after the oil pressure of the engine or the engine vacuum reaches a predetermined value at which time the engine is self operative. This type of switch is also well known and in the particular embodiment shown the switch comprises a fluid motor 80a containing the usual flexible diaphragm which is moved leftwardly when a predetermined vacuum pressure exists within chamber 80b. The diaphragm operates switch contacts 80c which are normally held closed by a spring 80d until the spring is overcome by vacuum in chamber 80b.

From the above it is apparent that when switch 82 and switch 80 are closed, current will flow from the battery 26 through lead 74 to the actuating coil 84, lead 96, junction 63, lead 62 where it will be grounded through the generator 60 at ground 50. The current flow through coil 84 will cause the armature to move and close contacts 90 and 92. When, however, the engine becomes self operative to cause the generator to produce a current and voltage, the voltage of the generator 60 will oppose the voltage of the battery and cause the voltage upon and current flow to the actuating coil 84 to become practically zero. When this occurs, the actuating coil will not be energized sufficiently to attract armature 88 and continue the closure of contacts 90 and 92. This arrangement provides a safety feature to cause the opening of contacts 90 and 92 when the prime mover is self-operative.

The switch 76 may be of any suitable type which is current responsive and may be of the type disclosed in U.S. Patent 2,699,161. This switch is of the hot wire type and will cause opening of the contacts 76a after a predetermined amount of current has passed through hot wire 76b for a predetermined time. This switch is also adapted to cause reclosure of the contacts 76a of circuit breaker 76 after the current flow therethrough has ceased for a predetermined time. The hot wire 76b of the circuit breaker 76 is preferably designed so that a prolonged current flow through both windings 30 and 32 of the solenoid 24 will cause the circuit breaker 76 to open, but neither the steady state value of current through winding 30 nor the instantaneous surge of cur-

rent through windings 30 and 32 will cause opening of the circuit breaker 76. The switch 76 includes a conducting frame 76c which is pivoted at 76d. A spring 76e constantly biases the frame 76c in a clockwise direction and toward an insulated stop. One of the contacts 76a is connected with one side of armature 88 while the other contact is electrically connected to one side of hot wire 76b and through a spring arm 76f to frame 76c. The frame 76c is electrically connected with lead 52. The hot wire 76b is formed of any suitable wire that elongates upon heating due to the passage of a current therethrough and which contracts upon cooling. Thus, when contacts 76a are closed, current flows through hot wire 76b and through frame 76c, the hot wire being heated during this time. The resistance of the hot wire and circuit through the frame 76c are so proportioned that upon prolonged current flow through windings 30 and 32 the hot wire elongates sufficiently so that spring 76e moves the frame to a position to open contacts 76a. When the wire 76b cools, it contracts and once more closes contacts 76a.

With the above circuit arrangement in mind, the operation thereof will now be described. When switch 82 is closed, the coil winding 84 will be energized to set up a magnetic attraction in core 86 to cause the movement of armature 88 to close the contacts 90 and 92. The closure of contacts 90 and 92 will cause the circuit from the battery to the armature 88 and circuit breaker 76 to be complete so that current will flow through lead 52 through both windings 30 and 32 of the solenoid 24. When current flows through windings 30 and 32, the plunger 34 will be attracted to move the pinion gear 54 toward the ring gear. If there is no tooth abutment between the gear teeth on the pinion 54 and ring gear 56, the solenoid plunger will travel a sufficient distance to the right to cause contact 38 to close the circuit between contacts 40 and 41 so as to complete the circuit from the battery to the starting motor. This in turn will cause the winding 32 to be deenergized so that the circuit breaker does not open the circuit to winding 30. When tooth end abutment occurs, the contact 38 is not moved sufficiently to engage the contacts 40 and 41 and current will continue to flow through both windings 30 and 32. This current flow will cause the hot wire of the circuit breaker 76 to cause an opening of the contacts of circuit breaker 76. When the contacts of circuit breaker 76 open the circuit to both windings 30 and 32 will be broken and the solenoid 24 will be deenergized in spite of the fact that the switch 82 is closed. After a predetermined period of time, the circuit breaker 76 will operate and reclose the circuit to windings 30 and 32 so the starter drive 22 is again moved toward the ring gear. Should abutment again occur, then the circuit breaker 76 will again open to repeat the cycle of deenergizing and energizing the coil windings 30 and 32. A repetition of the above cycles will cause starting motor and starter drive parts to finally move sufficiently so that the pinion gear is positioned to pass into meshing engagement with the ring gear. This will permit the starting motor to be energized to crank the engine. After the engine is self operative, the circuit to the actuating coil 84 will be opened or deenergized by the action of the switch 80 or the output of generator 60 to cause deenergization of the starting motor and the starting motor solenoid as heretofore described.

What is claimed is as follows:

In a starting system for an internal combustion engine having a ring gear that is adapted to mesh with a pinion, the combination comprising; a starting motor, a source of current for energizing said starting motor, a starter drive including a pinion bodily movable into cranking engagement with the ring gear of said engine for transmitting torque between said motor and engine, a first electric switch connected between said starting motor and said source of current for completing a circuit there-

between, a solenoid actuator including a first holding winding, a second winding and a movable plunger, means connecting said plunger with said starter drive for moving said pinion into engagement with said ring gear when said first and second solenoid windings are energized, means connecting said plunger and switch for operating said switch to a closed position only after said pinion has meshed with the ring gear, a second electric switch connected between said current source and said first and second solenoid windings for completing a circuit therebetween, means responsive to current flow of greater than a predetermined magnitude through said first and second solenoid windings for opening said second switch and for maintaining said second switch in an open position for a predetermined time interval, said second switch remaining closed at a value of current flow through said windings that is less than said predetermined magnitude, means for automatically reclosing said second switch

5 after said predetermined time interval to automatically initiate another attempt at shifting said pinion into mesh with said ring gear, and an electric circuit including said first electric switch for short circuiting said second solenoid winding when said first electric switch is closed.
